Patented Dec. 26, 1916.

UNITED STATES PATENT OFFICE.

NIC W. TRAUTNER, OF RED WING, MINNESOTA, ASSIGNOR TO RED WING SEWER PIPE COMPANY, OF RED WING, MINNESOTA.

SEWER-BLOCK

1,210,118.

Specification of Letters Patent. Patented Dec. 26, 1916.

Application filed October 30, 1915. Serial No. 58,863.

To all whom it may concern:

Be it known that I, NIC W. TRAUTNER, a citizen of the United States, residing at Red Wing, in the county of Goodhue and State of Minnesota, have invented a new and useful Sewer-Block, of which the following is a specification.

The device forming the subject matter of this application is a block adapted to be used 10 in the making of sewers, in the formation of roofs, and for other purposes.

The invention aims to improve the end joint of the block and to construct an end joint which may be fashioned readily in a 15 plastic, cellular block of that sort which is made in a press, the ends of the block being cut into shape.

Another object of the invention is to provide a block of the type described which, 20 when embodied in a sewer or like structure, will resist internal pressure as well as external pressure.

It is within the province of the disclosure to improve generally and to enhance the 25 utility of devices of that type to which the present invention appertains.

With the above and other objects in view which will appear as the description proceeds, the invention resides in the combination, 30 arrangement of parts and in the details of construction hereinafter described and claimed, it being understood that changes in the precise embodiment of the invention herein disclosed can be made within 35 in the scope of what is claimed, without departing from the spirit of the invention.

In the accompanying drawing:—Figure 1 shows in end elevation, a series of interlocked parts constructed in accordance with the 40 present invention; Fig. 2 is a top plan of the structure shown in Fig. 1; Fig. 3 is a perspective showing one of the blocks; Fig. 4 is a cross section on the line 4—4 of Fig. 1; Fig. 5 is a cross section on the line 5—5 of Fig. 1; Fig. 6 is a fragmental end elevation showing two of the blocks in the positions which the same will assume when the 45 ends of the block are alined; Fig. 7 is a side elevation of the structure shown in Fig. 6; Fig. 8 is a fragmental perspective showing a portion of the opposite edge of the block 50 from that which appears at the top of Fig. 3.

The block forming the subject matter of this application preferably is fashioned 55 from clay, or clay and concrete and is made

in a press, the joints being cut to proper shape. The block is denoted by the numeral 1 and is provided with a plurality of intermediate openings 2 extended longitudinally of the block and prolonged entirely there- 60 through. Between the openings 2 and the inner and outer surfaces of the block are formed outer openings 3 in radial alinement with the openings 2. The construction of the block therefore is such that the same em- 65 bodies spaced inner walls 4 and outer walls 5 spaced from the inner walls. Extended between the outer walls 5 and the inner walls 4 are longitudinal ribs 6, the inner walls 4 being held in spaced relation by ribs 70 7, the ribs 6 and 7 being in alinement trans- versely of the block.

In the longitudinal edge of the block 1 there is formed a groove 8 and in the opposite longitudinal edge of the block there is 75 formed a tongue 9, the tongue 9 being shaped to be received in the groove 8 of a like block. As indicated at 10, the tongue 9 is beveled so as to compact the mortar in the groove 8 and not force the mortar out 80 of the groove. At one end of the block there is formed a tongue 11 defining shoulders 12, the tongue 11 being provided with a longi- 85 tudinal opening 14. At the opposite end of the block there is formed a groove 15 adapted to receive the tongue 11 of a like block. In fashioning the groove 8 in the longitudinal edge of the block, the ribs 6 are not cut away entirely, but project onto the inner faces of the outer walls 5 of the block, as clearly 90 shown in Fig. 3, to serve as reinforcements or buttresses for the walls 5. Since the ribs 6 and 7 are in radial alinement, the block, at intervals, is reinforced by a continuous and unbroken cross wall, as will be under- 95 stood clearly when Fig. 3 is compared with Fig. 5. The tongues 9 on the longitudinal edges of the blocks are fashioned like the tongues 11 on the ends of the blocks, and consequently, the blocks in adjacent circum- 100 ferential courses may be laid with their ends alined, as indicated in Fig. 7 or with their ends in break joint order, as clearly indicated in Fig. 2.

Having thus described the invention, what 105 is claimed is:—

In a device of the class described, a block having a side groove along one longitudinal edge and provided along its opposite longi- 110 tudinal edge with a side tongue adapted to

be received in the side groove of a like block, the block being provided at one extremity with an end groove and being provided at its opposite extremity with an end tongue 5 adapted to be received in the end groove of a like block, the side and end tongues being of a like contour, whereby the blocks of adjoining courses may be placed with their ends aligned or in break-joint order, the 10 block having spaced passages defining inner walls, outer walls, inner ribs connecting the inner walls, and outer ribs connecting the outer walls with the inner walls, the outer ribs being extended onto the inner faces of

the outer walls, beyond the base of the side 15 groove, to form reinforcements at the extremities of the outer walls, and to form reinforcements between the extremities of the outer walls, the inner ribs terminating at the base of the side groove. 20

In testimony that I claim the foregoing as my own, I have hereto affixed my signature in the presence of two witnesses.

NIC W. TRAUTNER.
